(57) **CLAIM**

An ornamental design for a controller housing, as shown and featured in the accompanying drawings.

DESCRIPTION

FIG. 1 is a right, front, top perspective view of a controller housing in accordance with the present invention;
FIG. 2 is a right-side elevation view thereof;
FIG. 3 is a left-side elevation view thereof;
FIG. 4 is a back elevation view thereof;
FIG. 5 is a front elevation view thereof;
FIG. 6 is a top plan view thereof;
FIG. 7 is a bottom plan view thereof; and,
FIG. 8 is a left, rear, bottom perspective view thereof.
The broken lines represent portions of the structure that form no part of the claim.
